ATTORNEY.

UNITED STATES PATENT OFFICE.

ANDREW JAY CROSS, OF CHESTER, PENNSYLVANIA.

SPECTACLES.

SPECIFICATION forming part of Letters Patent No. 300,696, dated June 17, 1884.

Application filed April 23, 1884. (No model.)

To all whom it may concern:

Be it known that I, ANDREW JAY CROSS, a citizen of the United States, residing at Chester, in the county of Delaware, State of Pennsylvania, have invented a new and useful Improvement in Spectacles, which improvement is fully set forth in the following specification and accompanying drawings, in which—

Figure 1 is a top view of a pair of spectacles embodying my invention. Fig. 2 is a front view thereof. Fig. 3 is a top view showing the nose-piece and frames of the eye-pieces detached. Fig. 4 is a section of a modification.

Similar letters of reference indicate corresponding parts in the several figures.

My invention consists of an improvement in the nose-piece and frames of the eye-pieces of a pair of spectacles whereby said parts are firmly connected, the means employed therefor being simple, inexpensive, substantial, and reliable.

Referring to the drawings, A represents the frames of the eye-pieces of a pair of spectacles, and B the connecting nose-piece thereof. On the inner sides of the frames A are studs a, in which are openings, b, the ends of the studs being channeled, grooved, or slotted on their ends, forming lips c. The nose-piece has formed with or secured to it near each end a flange, d, the ends of said piece being adapted to enter the openings b, and the flanges d to enter the lips c, as most clearly shown in Fig. 3. When the nose-piece and frames are fitted together, the openings b and lips c being oc-

cupied, respectively, by the ends of the nose-piece and the flanges d thereof, said lips are bent down around or over said flanges by any suitable tool or implement, thus clinching the former on the latter and firmly connecting the nose-piece with the frames of the eye-pieces, 35 the projection of the ends of the nose-piece into the studs increasing the length of the connection of the parts, and consequently the strength of the same.

In Fig. 4 the position of parts is reversed, 45 the lips and openings being on and in the ends of the nose-piece and the flanges on the studs, without, however, producing different effects from those hereinbefore stated.

Having thus described my invention, what 50 I claim as new, and desire to secure by Letters Patent, is—

The connection of the nose-piece of a pair of spectacles with the frames of the eye-pieces thereof, by means of flanges on said nose-piece and lips and openings on and in the studs of the frames, the ends of the nose-piece entering the openings of the studs, and the flanges entering the lips, said lips being bent over or on the flanges by any suitable tool or 55 implement, thus clinching the lips on the flanges and firmly connecting the nose-piece and frames of the eye-pieces.

ANDREW JAY CROSS.
